REFORMING OF NAPHTHA

Eugene J. Houdry, Philadelphia, Pa., assignor to
 Houdry Process Corporation, Dover, Del., a corporation of Delaware

Application April 27, 1935, Serial No. 18,600

6 Claims. (Cl. 196—52)

This invention relates to the treatment of hydrocarbon distillates of mineral oil and the like at the upper end of the gasoline boiling range and has as its primary purpose the improvement 5 of the antiknock characteristics of the material treated. Another and related object is to effect a general or a partial lowering of the boiling range. Still another object is to reduce the sulphur content of the material treated. Still another object 10 is to produce the above results with a minimum of loss.

To meet the requirements of automotive engines and the specifications for motor fuels suitable therefor refiners have resorted to various expedients to improve the antiknock ratings of their products. One expedient is to mix with the finished product a chemical substance which modifies the rate of combustion of the fuel so as to suppress to some extent detonating effect of the fuel, 15 one such substance being tetraethyl lead, known under such names as ethyl spirit or Q fluid. Such substances, being highly poisonous, are dangerous to handle and expensive to manufacture. Moreover the number of octane points rise which can 20 be effected by the addition of such substances varies widely with the composition of the motor fuel and in some instances is quite negligible.

Another expedient is the thermal reforming of knocking hydrocarbons by the use of heat and 25 pressure. Since the low boiling fraction of straight run gasoline contains the non-knocking components, refiners have found it necessary, in many instances, to reform the higher boiling or knocking part of natural gasoline to secure an adequate quantity of standard grade gasoline. The operation is, in most instances, conducted at 30 a cracking temperature, namely, above 950° F., and at pressures in excess of 400 pounds in a once through operation. Temperature and pressure 35 conditions are set to produce a predetermined gas make, inasmuch as the gas make in this operation is directly related to the octane rating of the product. The gas make is high and normally varies from 15% up to 30 or even 35%, depending upon the nature of the stock and the octane 40 rating desired. Hence the thermal operation of reforming is costly by reason of the heavy losses.

Many attempts have been made in recent years 45 to effect reforming by catalysis and there are disclosures in patents of I. G. Farbenindustrie Aktiengesellschaft and others specifying a wide range of catalysts and of operating conditions including temperature ranges from 572 to 1500° F., pressures from subatmospheric to in excess of 50 200 atmospheres, feed rates of 1:2 (one volume of

oil per hour to two volumes of catalyst) to 3:1 per hour. The U. S. patent to M. W. Boyer, No. 1,934,031, issued November 7, 1933, specifies temperatures above 900°, 950° or 1000° F., pressures above 20 atmospheres and preferably above 200 atmospheres, a feed rate of 2:1, and operation continuously with added hydrogen. So far as I am aware, none of the proposed catalytic reforming processes has gone into commercial use or has been found to be capable of successful competition with thermal reforming or with octane increase by the addition of chemicals.

During the development of various processes for the conversion or treatment of petroleum with the aid of contact masses I have made many attempts to effect catalytic reforming of heavy naphtha with indifferent success. After an exhaustive and detailed study extending over a long period, with thousands of experiments, I have 15 finally discovered that heavy naphtha can be reformed by a new method of procedure with remarkably favorable results, especially when the 20 operation is effected catalytically.

The drawing shows a flow sheet of the process 25 of this application.

The first step in the new procedure is to divide the naphtha by fractionation or otherwise into two parts, the first part covering the boiling range of about 250° to 375° F. and the second part from 30 about 375° F. to the end point of the naphtha. These two parts are then reformed separately as follows: Each part undergoes the chosen reforming operation and from the product is separated the reformed material of the desired antiknock 35 value, such as 75 octane, leaving a low octane residue. This residue is then reformed and the 75 octane material again removed, the procedure continuing until all the material of each part is brought to the desired octane rating. While thermal reforming may be used with a certain measure of success, I prefer to use a catalytic reforming 40 operation, since it gives a larger percentage of easily separated material of the desired octane rating, but the operating conditions are critical and divergence from any of them beyond a relatively narrow range is sufficient to upset yield, or 45 product, or both.

The results of the initial fractionation of the charge combined with separate catalytic reforming of the fractions are most surprising and unexpected. In the first place, liquid yield as high 50 as 100% is attainable. In the second place, the octane rating of the converted product is above 70 and usually about 75 (C. F. R. Motor Method), regardless of the charging material. In the third 55

place, the gas make has little or no effect upon the antiknock improvement of the charge.

Factors in the most successful operation of my process comprise, catalyst, temperature, pressure, feed rate or time of contact of reactants, length of period on-stream (which takes into account the changed characteristics of the catalyst due to deposit of contaminants as the reaction period progresses), and added gaseous material, in addition to the particular nature of the hydrocarbon charge. Preferred conditions of temperature and/or pressure vary, for example, as the feed rate or activity of the catalyst varies. By way of illustration as the time of contact of reactants with the catalyst is increased, the temperature and/or pressure may be reduced somewhat, and vice versa. Illustrative relative conditions of operation appear hereinafter.

Salient features of the present invention involve: (1) maintaining the fraction of reactants charged to a reforming zone within a relatively or fairly narrow boiling range, e. g. dividing the raw naphtha charge into fractions, one boiling below substantially 375° F. and another boiling above substantially 375° F. or dividing the naphtha charge into fractions each having a boiling range of approximately 100° F. and (2) controlling the rate of feeding the naphtha fraction to the catalyst as herein defined and illustrated. Reforming in a series of separate passes, is, inter alia, also an important feature of this invention.

The charge most particularly contemplated is a naphtha predominately in the boiling range of 250° to 450° F. which is divided into two or more fractions, e. g., 250° to 375° F. and 375° F. to end point respectively. These parts must be reformed separately. Several passes are usually required for best results.

The catalyst is essentially a blend of silica and alumina with as little extraneous material as possible. The weight ratio of silica and alumina should be not less than three to one, preferably four to one, or somewhat higher. The catalyst may be formed in various ways, as for example, precipitating silica on alumina, or alumina on silica, or by combining a silica gel with alumina. Another way is to take a natural compound, such as a clay in the form of fuller's earth, kieselguhr, bentonite, china clay, or the like, and then leach it with acids or treat it with other substances such as phosgene and various alkalies. The resulting product is used as a base or carrier on which to build back the desired silica to alumina ratio. In some instances, improved results are secured by incorporating in the catalyst a small quantity of the oxide of one or more of the following metals—iron, lead, copper, manganese, vanadium, molybdenum, chromium, tungsten. The catalyst is formed in bits, broken fragments, or molded pieces of substantially uniform size so as to be capable of regeneration in place.

The temperature must be between 850° and 925° F. and preferably between 875° and 925° F.

The pressure may vary between 15 and 300 pounds per square inch gauge. An excellent operation is secured at 75 pounds. One advantage obtained by raising the pressure up to 300 pounds is an improvement in the rate of feed.

The feed rate may vary from 3:5 (three volumes of oil per hour to five volumes of catalyst) to 7:5. A good rate for seventy-five pounds pressure is 1:1.

The period of operation varies from one-half to two hours, and comprises the time necessary

to feed to the catalyst a quantity of oil varying from one-fourth the volume to a volume equal to twice that of the catalyst. The run generally averages from forty-five minutes to one and one-half hours, the catalyst being thereafter regenerated to remove coke and tarry deposits in preparation for another run.

Extraneous gaseous material, in the form of steam or refractory gases such as methane, ethane, propane, butane, hydrogen or mixtures of the same, is added to the extent of from 2 to 5% by weight of the charge for the purpose of inhibiting secondary reactions and to reduce the deposit of contaminants upon the catalyst.

The operation is conducted so as to produce only a small amount of gas, as of the order of 4 to 7% per pass. This is enough to insure a good reaction and nothing is gained by making more gas. The products of the reaction are topped by fractionation to separate out the lower boiling converted material of increased octane rating, as above 70. Normally about 50% of the charge is converted into high octane material. The remainder, which usually shows some slight improvement in octane over the charge, may be subjected, with or without fresh charge, to a second converting operation, and the procedure continued until all the material is converted. Since the charge is changed into lower gravity material, and since the gas make and the carbon deposit are low, the yield in liquid is very close to 100%.

First example

An East Texas heavy naphtha of an A. P. I. gravity of 47.6 and boiling range of 236 to 470, with an octane rating of 38 by the C. F. R. Motor Method, was divided into two cuts, a 65% overhead with a gravity of 50.5, a boiling range of 236 to 380, with an octane rating of 43, and a 35% bottom cut of a gravity of 41.7 and a boiling range of 375 to 470, having an octane rating of 29.

The 65% or light cut was fed to a catalytic mass of the above described type maintained at a temperature of 875° F., at a charging rate of 1:1, under 75 pounds pressure, with 2% of steam, for one hour. The gas make was 4.3% by weight and the coke deposit on the catalyst 1.5%, the resulting products being topped to 50% secure a 39% overhead having an octane rating of 72.7. The recycle material was sent in a second pass into the conversion zone under the same operating conditions, except that the reaction temperature was raised to 900° F. The gas make was 5% by weight and the coke deposit on the catalyst 1.8%, and a high octane overhead cut comprising 42% of the products was separated out having an octane rating of 70.7. The bottoms or recycle material from the second pass was sent for a third pass under the same operating conditions as for the second pass, except that the charging rate was reduced to 4:5. The gas make was 5.5% by weight and the coke deposit on the catalyst 3.3%, and the products were topped to obtain a 40% yield of 73.7 octane gasoline. The overall yield for the three passes was 73% of gasoline with an octane rating of 72 (C. F. R. Motor Method). There was approximately 20% of recycle material remaining having an A. P. I. gravity of 40, a boiling range of 315 to 470, and an octane rating of 50.

The 35% bottoms of the East Texas naphtha were catalytically converted separately as follows: The first pass was made at a charging rate

of 3:8 with 5% steam to catalyst of the above described type, under 65 pounds pressure at a temperature of 882° F. for 45 minutes. The gas make was 7% and the coke deposit 1%, and 48% overhead of 80 octane rating was separated from the products. The bottoms or recycle material were sent in a second pass under the same operating conditions as the first pass, the gas make being 6.6% and the coke deposit 1%, and a 48% overhead of 80 octane rating was again taken from the products. For the third pass, the operating temperature was raised to 900° F., the other conditions remaining the same, the gas make being then 7% and the coke deposit on the catalyst 1.2%, and 44% of the overhead products was separated out, having an octane rating of 80 (C. F. R. Motor Method). The final yield for the three passes from the 35% bottom cut of East Texas naphtha was 83% of 80 octane gasoline and 13% of recycle material of 50 octane rating.

The total average yield from the reforming operation on both cuts of the original heavy naphtha was 76.3% of gasoline of 76 octane rating (C. F. R. Motor Method). The bottoms left, suitable for recycling, comprised 17.5% of the original charge with a 50 octane rating.

Second example

A California naphtha of 40.5 A. P. I. gravity, with a boiling range of 300 to 495 and an octane rating of 32, was divided into a light cut of approximately 35%, having a gravity of 46.8, and a boiling range of 300 to 375, with an octane rating of 40, and a heavy cut approximating 65%, having a gravity of 38.3, a boiling range of 375 to 495, and an octane rating of 28. Each cut was separately reformed in three passes.

Taking first the light cut, the first pass was effected on a catalyst of the above described type at 875° F., 75 pounds pressure, at a rate of 1:1, with 2% of extraneous gas such as steam for 57 minutes, producing 4.5% of gas and 1% coke and yielding 40% of 76 octane gasoline. The bottoms from the first pass were subjected to a second pass under the same conditions, except that the feed rate was 4:5 and produced 4.4% gas and 1% coke, with a yield of 39.6% gasoline of 76 octane. The bottoms from the second pass were subjected to a third pass under the same operating conditions as the first pass, except that the temperature was raised to 900° F. The gas make was 5% and the coke deposit 1.2%, the yield being 38.2% of 76 octane rating. The total yield for the light cut was 76% of 76 octane gasoline (C. F. R. Motor Method) and about 20% of recycle material having an octane rating of 50.

For the heavy cut of California naphtha, the first pass was made on the catalyst at 875° F. at a charging rate of 4:5 under 55 pounds pressure with 5% of steam for 45 minutes. 6% of gas was produced and there was a coke deposit of 2% on the catalyst. The products were subjected to fractionation, obtaining an overhead cut of 40% gasoline of 80 octane rating. The bottoms from the first pass were subjected to a second pass under the same conditions producing 6.2% gas, a coke deposit of 1.8% and yielding 41% of 80 octane gasoline. The third pass was made at 900° F., the other conditions being the same and the gas make was 6.1%, the coke deposit 2.1% and the yield of 80 octane gasoline was 38.7%. The total yield for the heavy cut was 75% of 80 octane gasoline (C. F. R. Motor

Method) and 18% of recycle material of 50 octane.

When the products from both cuts were blended, the total yield for the California naphtha reformed was 75.35% of 78 octane gasoline and 18.7% of heavy material suitable for further recycling of 50 octane rating.

Third example

A Michigan (Mt. Pleasant) heavy naphtha, having an A. P. I. gravity of 51.8 and a boiling range of 300 to 450 with an octane rating of -0 (C. F. R. Motor Method) was separated into a light cut having a boiling range of 300 to 375 and a heavy cut boiling in the range of 375 to 450. Both cuts had a -0 octane rating.

The light cut, which approximated 65% of the original material, was subjected to four passes. The first pass was sent to a catalyst of the above described type maintained at 875° F. at a charging rate of 7:10 with 2% of steam under 75 pounds pressure for 60 minutes. The gas make was 7%, the coke deposit on the catalyst 1.5%, and the products, when topped, yielded 25% of gasoline of 72 octane rating (C. F. R. Motor Method). The second pass was at the rate of 4:5, with the catalyst at 900° F., the other conditions being the same, producing 6.8% of gas, a coke deposit of 1.4%, and yielding 23.2% of 72 octane gasoline. The third pass was made at the rate of 7:10 under conditions otherwise the same as in the second pass, producing 7.2% of gas, a coke deposit of 1.6%, and yielding 24.5% of 72 octane gasoline. The fourth pass was made under the same conditions as the third, with a gas make of 6.8%, a coke deposit of 1.6%, and yielding 23.5% of 72 octane gasoline. The final yields for the four passes of the light cut were 61% of 72 octane gasoline (C. F. R. Motor Method) and 24% of bottoms or recycle material of -0 octane rating.

The heavy Michigan cut, comprising 35% of the original material, was subjected to three passes. The first pass was made on catalyst of the above described type at 875° F. at a charging rate of 4:5 with 5% steam at 55 pounds pressure for 45 minutes. The gas make was 7.5, the coke deposit 2%, and the yield was 32% of 72 octane gasoline (C. F. R. Motor Method). The second pass was made on the catalyst at 900° F., at a charging rate of 7:10, with 5% steam and under 65 pounds pressure, producing a gas make of 7.8%, a coke deposit of 2.8% and yielding 28.5% of 74 octane gasoline. The third pass was made under the same conditions as the second pass with a gas make of 7.7%, a coke deposit of 2.9%, and the yield was 28% of 74 octane gasoline. The total yield of the three passes of the heavy cut was 61.5% of 73 octane gasoline (C. F. R. Motor Method) and the bottoms or recycle material of -0 octane which remained was 29.5%.

The products of both the heavy and the light cuts, after reforming, when blended, gave 61.2% of 72 octane gasoline and 25.9% of bottoms suitable for further recycling of -0 octane rating.

The gas produced from all operations in accordance with the present invention is of high quality. It has a high specific gravity (1.3 to 1.5) and a high olefinic content. By removing from the gas all of the constituents which are in the gasoline boiling range, such as butane and heavier, a considerable quantity of gasoline of a very high octane rating, over 90 (C. F. R. Motor Method) can be recovered which is suitable for blending with the reformed naphtha or with

other gasoline. Also, the olefins contained in the gas can be polymerized to produce a further yield of gasoline of high octane number. By these means, the total yield of high octane gasoline can be raised, in some cases, as much as 8 to 10%, and the octane number by two points.

In order to determine where to cut the product to separate out the transformed material of the desired octane rating, it is customary to make an experimental run on laboratory apparatus with the charging stock under suitable predetermined conditions. It is then found, for example, that a 40% overhead fraction gives an 80 octane, that a deeper cut such as 46% gives 77 octane, and that a still deeper cut such as 56% will give a 73 octane. Thus it is possible to cut for a definite octane value of the reformed material, or to obtain a definite yield, as 50%, taking the octane improvement which such a yield offers.

20 I claim as my invention:

1. In the reforming of a naphtha charge to improve its antiknock characteristics, the process which comprises dividing the charge into a plurality of fractions of different boiling range characteristics, each having a boiling range of not more than 125° F., subjecting each of said fractions to a separate reforming operation, each of said operations involving treating the respective naphtha fraction in a plurality of separate reaction steps, the low boiling portions of the products from each reaction step which have an octane rating above approximately 70 C. F. R. M. M. being separated from the remaining higher boiling or bottoms fraction before the latter is subjected to the next succeeding reaction step, each of said steps being effected in a reaction zone containing a catalyst comprising a blend of silica and alumina and being maintained under a superatmospheric pressure not greater than approximately 300 lbs./sq. in. gauge, and at a temperature within the range of 850° to 925° F., and blending the products of each of the reforming steps having an octane rating above approximately 70 C. F. R. M. M. to provide a high yield of high quality product from said naphtha charge and a low concomitant production of coke and fixed gas.

2. In the reforming of a naphtha charge to improve its antiknock characteristics, the process which comprises dividing the charge into a plurality of fractions of different boiling range characteristics, a predominant proportion of each boiling within a range of not more than 100° F., subjecting each fraction separately, in at least one confined reaction zone, to the action of an adsorptive contact mass contained therein, said mass comprising a blend of silica and alumina with the permissible addition of other active material and being maintained at a superatmospheric pressure not greater than approximately 300 lbs./sq. in gauge and at a temperature approximately within the range of 850° to 925° F., and blending together at least a portion of the products from the said reaction zones having an octane rating above a predetermined satisfactory minimum so as to effect the desired improvement in anti-knock characteristics of low boiling components as well as of high boiling components of the aforesaid charge while keeping the concomitant production of coke and fixed gases at a low amount in proportion to the amount of said charge.

3. In the reforming of a naphtha charge boiling substantially completely below approximately 450° F. to improve its antiknock characteristics,

the process which comprises dividing the naphtha charge into at least two fractions of different boiling range characteristics, a first fraction boiling predominantly above 375° F. and a second fraction boiling predominantly below 375° F. and subjecting each fraction to a separate plurality of reforming steps in separate reaction zones held at progressively increasing temperatures, the lower boiling fraction of the products from each of said reaction zones having an octane rating above a predetermined minimum being separated from the remaining or bottoms fraction before the latter is subjected to the next succeeding reaction step, each step being effected in a reaction zone containing an adsorptive contact mass comprising a blend of silica and alumina and being maintained under a superatmospheric pressure not greater than approximately 300 lbs./sq. in. gauge and at a temperature substantially within the range of 850° to 925° F.

4. In the reforming of a naphtha charge boiling substantially completely below approximately 450° F. to improve its antiknock characteristics, the process which comprises dividing the naphtha charge into two fractions of different boiling range characteristics, a first fraction boiling predominantly above 375° F. and a second fraction boiling predominantly below 375° F., subjecting each fraction to a separate reforming operation in contact with an adsorptive siliceous mass maintained approximately at a temperature within the range of 850° to 925° F. and under superatmospheric pressure, and blending together portions of the products of the higher and lower boiling fractions of said charge which have an octane rating above a predetermined satisfactory minimum so as to arrive at a high yield of high quality product while keeping the concomitant production of coke and fixed gases at a low amount in proportion to the amount of the aforesaid charge.

5. In the reforming of a naphtha fraction to improve its anti-knock characteristics, the process which comprises subjecting the naphtha in straight passes to a first reforming step at a temperature of about 875° F., fractionating the products of the first reforming step so as to obtain an overhead fraction of at least 70 octane rating C. F. R. M. M. and a first bottoms fraction, subjecting said first bottoms fraction to a second separate reforming step at a temperature of about 900° F., fractionating the products of said second reforming step so as to obtain an overhead fraction of at least 70 octane rating C. F. R. M. M. and a second bottoms fraction, passing said second bottoms fraction to a third reforming step wherein it is subjected to a temperature of about 925° F. and separating the products of said third reforming step into an overhead fraction of at least 70 octane rating C. F. R. M. M. and a lower octane bottoms fraction, each of said reforming steps being conducted under a suitable superatmospheric pressure of the order of approximately 75 lbs./sq. in. gauge and in the presence of catalytic masses, each comprising essentially blends of silica and alumina having a weight ratio of silica to alumina of at least approximately 4 to 1.

6. In the reforming of a naphtha charge boiling substantially completely below approximately 450° F. to improve its antiknock characteristics, the process which comprises dividing the naphtha charge into at least two fractions of different boiling range characteristics, a first fraction boiling predominantly above 375° F. and a second fraction boiling predominantly below 375° F., subjecting

5 said first fraction in successive passes to a first reforming step at a temperature of about 875° F., fractionating the products of the first reforming step so as to obtain an overhead fraction of at least 70 octane rating C. F. R. M. M. and a first bottoms fraction, subjecting said first bottoms fraction to a second separate reforming operation at a temperature of about 900° F., fractionating the products of the second reforming step 10 or operation so as to obtain an overhead fraction of at least 70 octane rating C. F. R. M. M. and a second bottoms fraction, passing said second bottoms fraction to a third reforming step wherein it is subjected to a temperature of about 825° F.

and separating the products of said third reforming step into an overhead fraction of at least 70 octane rating C. F. R. M. M. and a lower octane bottoms fraction, and subjecting the aforesaid second fraction to at least one separate reforming step, each of said reforming steps being conducted under the suitable superatmospheric pressure of the order of approximately 75 lbs./sq. in. gauge and in the presence of catalytic masses, each comprising essentially blends of silica and alumina having weight ratio of silica to alumina of at least approximately 4 to 1. 10

EUGENE J. HOUDRY.
